UNITED STATES PATENT OFFICE.

MATTHEW T. CHAPMAN, OF AURORA, ILLINOIS, ASSIGNOR TO THE AMERICAN WELL WORKS, OF AURORA, ILLINOIS, A CORPORATION OF ILLINOIS.

WELL-SINKING APPARATUS.

1,197,790.

Specification of Letters Patent. Patented Sept. 12, 1916.

Application filed June 30 1913. Serial No. 776,591.

To all whom it may concern:

Be it known that I, MATTHEW T. CHAPMAN, a citizen of the United States, residing at Aurora, in the county of Kane and State of Illinois, have invented certain new and useful Improvements in Well-Sinking Apparatus, of which the following is a specification, reference being had to the accompanying drawings.

10 This invention relates to well sinking apparatus and it has for its object the provision of new and improved means for inserting into the well or taking out of the well the pipes used for boring purposes.

15 As is well understood in the art, the boring pipes are used in lengths of about twenty feet ordinarily joined together by screw-threaded couplings. It is sometimes necessary to remove the boring pipe from the well

20 quite frequently, and it is therefore necessary that efficient means be provided for the withdrawal and replacing of said pipes.

To this end my invention has for one of its specific objects the provision of an improved elevator, as the device is known in the art, by which the lower section of pipe is held against rotation as the upper section is screwed out of the coupling when removing the boring pipe from the well.

25 30 means by which I have accomplished these objects are illustrated in the drawings and are hereinafter specifically described.

That which I believe to be new is set forth in the claims.

35 In the drawings,—Figure 1 is a central vertical section through the upper portion of the well pit and the apparatus mounted at that point; Fig. 2 is a horizontal section taken substantially on line 2—2 of Fig. 1; Fig. 3 is a horizontal section taken substantially on line 3—3 of Fig. 1; Fig. 4 is a vertical section taken substantially on line 4—4 of Fig. 3; Fig. 5 is a view from the right of the part shown in Fig. 4.

40 45 Referring to the several figures of the drawings in which corresponding parts are indicated by the same reference characters,—15 indicates a frame located at the upper end of the well pit 16 and having mounted thereon a bed-plate 17, rising from which is an annular sleeve 18.

45 50 55 59 indicates a series of anti-friction rollers mounted in a suitable annular channel in the bed-plate 17, being adapted to run therein upon a hardened ring 20,

21 indicates a hardened ring mounted upon the anti-friction rollers 19.

22 indicates the turntable or rotary of my device revolvably mounted upon the sleeve 18 supported by the anti-friction rollers 19.

23 indicates a bracket mounted upon the bed-plate 17 and extending inward over a flange 24 carried by the lower end of the rotary 22 being adapted to hold the rotary 65 from displacement.

25 indicates a shaft driven from any suitable source of power.

26 indicates a beveled gear keyed upon the shaft 25 and meshing with suitable teeth 70 27 carried by the rotary 22 whereby said rotary may be driven in either direction about the sleeve 18.

28—29 indicate posts loosely mounted in sockets 30—31, respectively, in the rotary 22. 75 32 indicates a plurality of additional sockets formed in the rotary 22 adapted to receive upright posts similar to the posts 28—29 when desired.

33 indicates a cover-plate mounted upon 80 the upper end of the sleeve 18, being held against rotation relative thereto by teeth 34 engaging suitable notches in the upper end of said sleeve.

35—36 indicate the two members of the 85 elevator pivoted together by means of a pin 37, best shown in Figs. 3 and 4, so as to be adapted to be clamped together about a boring pipe.

38—39 indicate sections of a boring pipe 90 joined together by a screw-threaded coupling 40.

Each of the members 35—36 of the elevator has pivotally mounted upon its inner face a clamping block 41, being secured in 95 position therein by means of a pin 42 the ends of which are free to move along grooves 43 in the said members, as shown in Fig. 1.

44 indicates set-screws, one secured by means of screw-threads in each of the members 35—36 with its inner end in contact with the outer end of the block 41 whereby said blocks may be moved toward each other to grip a pipe or other part, said blocks being toothed on their inner faces.

45 indicates set-screws mounted in the members 35—36 at each side of the block 41 therein.

46 indicates blocks of rubber or other resilient material interposed between the in- 110

ner ends of the screws 45 and the sides of the block 41 in each of said members 35-36.

47 indicates a clip pivotally mounted in the free end of the member 35 and adapted to be turned up over the free end of the member 36 so as to hold said two members in position about a pipe.

48-49 indicate laterally extending lugs upon the members 35-36, respectively, the 10 ends of which lugs are turned up into vertical position to be engaged by a suitable opening in the end of the clip 47. As best shown in Fig. 3, the clip 47 when turned into locking position extends clear to the 15 pipe 39 clamped by the elevator.

50-51 indicate oppositely-disposed lugs at one side of the opening through the cover-plate 33, and 52-53 indicate similar lugs at the opposite side of said opening. As best 20 shown in Fig. 5, the adjacent faces of said lugs are beveled and of such a distance apart as to receive the elevator 35-36 in closed position between them.

54-55 indicate buttons extending from 25 the members 35-36 for the insertion of links for raising the elevator, as will be readily understood.

It will be understood that in practice two elevators such as that just described will be used, one in the position shown in Fig. 1, and another at the upper end of the pipe section 38. With the pipes 38-39 being held in suspension by means of an elevator at the upper end of the pipe 38, the mode 30 of applying the elevator shown will be as follows: The pipe sections 38-39 would first be raised above the position shown in Fig. 1, whereupon the two members 35-36 of the elevator would be placed in position 35 about the pipe section 39. The clip 47 would then be turned into the position shown in Fig. 4 with its inner end against the pipe 39 and with the lugs 48-49 of the said two members extending through the opening in 40 said clip 47. The elevator would then be raised upon the pipe section 39 until the inner end of the clip 47 was brought against the lower edge of the coupling 40, whereupon the two sections of pipe 38-39 with 45 the elevator in position thereon would be lowered until the elevator was brought into engagement with the cover-plate 33 between the lugs 50-51 at one side and the lugs 52-53 at the other side. The screws 44 would then be tightened bringing the inner 50 ends of the blocks 41 into forcible contact with the coupling 40 below the central horizontal line of said coupling, as shown in Fig. 1. The clamp members 35-36 would 55 then be held in locked relation to each other not only by the clip 47 but also by the diagonally-positioned lugs 50-51-52-53 at opposite sides of said two members. In this 60 way the weight of the line of boring pipes is brought into play to hold the elevator sec- 65

tions 35-36 in clamped position upon the coupling 40. By reason of the engagement of the clip 47 by the coupling 40, said clip is insured against accidental disengagement. By reason of the provision of the lugs 48-49 embraced by the clip 47, additional security is given to the elevator for the raising and supporting of the boring pipes. By reason of the engagement of the blocks 41 upon the coupling 40 at or below its central horizontal plane only, the clamping force of the elevator is prevented from causing an undue springing of the sides of the pipe section 38 toward each other whereby it would be difficult to unscrew the section 38 from the coupling 40.

Coming now to a description of the means by which the upper section of pipe is turned in either direction as desired when the lower section is being held against rotation by the elevator 35-36, 56-57 indicate sockets pivotally mounted upon the posts 28-29, respectively, being held in position thereon by suitable collars 58. 59-60 indicate blocks of rubber mounted in the sockets 56-57 being provided with suitable openings for the insertion of wrench handles 61-62, respectively. 63 indicates a clamp member pivotally connected with the handle 61, and 64 indicates a clamp member pivotally connected with the clamp member 63. 65-66 indicate clamp members similarly connected together and connected with the handle 62. As best shown in Fig. 2, each of the clamp members 63-64-65-66 is provided upon 100 its inner face with suitable teeth by which it is adapted to bite into a pipe upon which it is tightened. As best shown in Fig. 2, the handle 61 is provided with a curved arm 67 which is adapted to engage a suitable hook 105 68 in the end of the clamp member 66. 69 indicates a curved arm extending from the handle 62 adapted to engage a hook 70 formed in the end of the clamp member 64. As will be readily understood, with the 110 tongs or wrench applied to the pipe 38, as shown in Fig. 2, if the handles 61-62 be turned in counter-clockwise direction in said figure the clamp members 63-64-65-66 will be tightened upon the pipe and a further exertion of force upon said handles 61-62 in the same direction,—as by a rotation of the rotary 22 in a counter-clockwise direction in said figure,—will cause a corresponding rotation of the pipe 38. On the 115 other hand a movement of the handles 61-62 in clockwise direction in said Fig. 2 will manifestly cause said handles to turn upon their pivotal connections with the clamp members, freeing the arms 67-69 120 from the hooks 68-70, respectively, and releasing the wrench entirely from the pipe. If it were desired to turn the pipe 38 in clockwise direction, this could be accomplished by the application of the wrench in 125

inverted position, as will be readily understood. When the wrench members have been freed from engagement with the pipe it is apparent that they may be pushed back 5 out of the way by reason of the resiliency of the parts 59—60, in which position they will be ready for use at a later time without the necessity for lifting them again into position. It will be understood that as the 10 pipe 38 is screwed out of the coupling 40 the pipe will be raised relative to the sockets 56—57 by a distance approximately equal to one-half the length of the couplings 40, thus bringing the inner ends of the handles 15 61—62 by such a distance higher than their outer ends. This is made practical by the use of the resilient blocks 59—60.

By the use of my improved form of wrench the possible slipping of the wrench 20 upon the pipe is prevented from causing any damage. As will be readily understood, when two separate wrenches are used one connected with the standard at one side of the rotary and the other connected with the 25 standard at the other side of the rotary, when one wrench slips the rotation continues through the medium of the other wrench alone. The application of power for rotating the pipe at one side is likely to 30 force the pipe to one side and in some cases even causes a breakage of the pipe. In the use of my improved wrench, when one of the chains of clamping blocks slips the other chain of clamping blocks is also loosened 35 35 upon the pipe and the driving ceases entirely until both chains again simultaneously grip the pipe.

Inasmuch as the gripping blocks carried 40 by the elevator members are of a greater radial length about their pivot points at the side edges than at the central point, it is evident that as said gripping blocks are turned on their pivots the gripping blocks are caused to bite into the pipe and to hold 45 it very firmly against rotation.

In the use of my improved construction 50 for boring purposes, the wrench above described is applied to the boring pipe just as it would be for screwing the sections of the 55 boring pipe together. When the pipe trembles or jumps as it does in the operation of boring, the wrench is adapted to slip longitudinally of the boring pipe which follows up the advance of the drill, by reason of the 60 jar upon the wrench and by reason of the fact that the gripping teeth of the wrench are vertically disposed, but the wrench is held normally against turning relative to the boring pipe. The elevator is 65 not used during the boring operation, adjacent to the cover-plate and the wrench may rest upon the cover-plate or may be mounted higher on the posts 28—29 as desired according to the requirements in the process 70 of boring.

While I have shown the part 33, by which the elevator 35—36 is supported and held against rotation, in the form of a cover-plate it will be understood that I do not restrict myself to that particular form of device except as hereinafter specifically claimed, inasmuch as any suitable means to this end may be used. 70

While I prefer to use the form of wrench shown in the drawings comprising handles 75 61—62 suitably mounted upon the rotary, I do not restrict myself to that particular form of wrench, except as hereinafter specifically claimed, the essential point being that the gripping means of the wrench is 80 caused to rotate with the rotary and to turn the pipe with it.

That which I claim as my invention, and desire to secure by Letters Patent, is,—

1. In a well-sinking apparatus, the combination of a bed-plate having an opening for the passage of a boring pipe, a holding member supported from said bed-plate, means for holding said holding member against rotation relative to said bed-plate, 90 a two-part elevator resting on said holding member,—said elevator comprising means for holding its two members in closed position clamped upon a boring pipe, and means for holding the pipe against rotation relative to the elevator,—and lugs extending upward from the upper face of said holding member between which the elevator is adapted to be seated, said lugs on opposite sides of said elevator serving to hold the 100 elevator closed about said pipe and to hold the elevator against rotation relative to the holding member.

2. In an elevator, the combination of two members hinged together, a clip for locking 105 said members in clamping position upon a pipe, and gripping blocks pivotally mounted in said members respectively at opposite sides of the elevator adapted to simultaneously engage the pipe and hold it against 110 rotation.

3. In an elevator, the combination of two members hinged together, a clip for locking said members in clamping position upon a pipe, gripping blocks one pivotally mounted 115 in each of said members for engaging the pipe and holding it against rotation, each of said blocks being movable radially in its member, and means for adjusting said blocks toward and from the pipe.

4. In an elevator, the combination of two members hinged together, a clip for locking 120 said members in clamping position upon a pipe, gripping blocks one pivotally mounted in each of said members for engaging the pipe and holding it against rotation, each of said blocks being movable radially in its member, and set-screws one mounted in each member for forcing the gripping block of that member toward the pipe. 130

5. In an elevator, the combination of two members hinged together, a clip for locking said members in clamping position upon a pipe, gripping blocks one pivotally mounted in each of said members upon a pin slidable radially in grooves in said member, said blocks being adapted to engage the pipe and hold it against rotation, and means for adjusting said blocks toward and from the pipe.
6. In an elevator, the combination of two members hinged together, a clip for locking said members in clamping position upon a pipe, gripping blocks one pivotally mounted in each of said members upon a pin slidable radially in grooves in said member, said blocks being adapted to engage the pipe and hold it against rotation, and set-screws one mounted in each member for forcing the gripping block of that member toward the pipe.
7. In an elevator, the combination of two parts hinged together, a clip for locking said members in clamping position upon a pipe, gripping blocks one pivotally mounted in each of said members for engaging the pipe and holding it against rotation, and resilient means mounted adjacent to each of said gripping blocks against which said gripping blocks rest when the pipe is held against turning through the medium of the elevator.
8. In an elevator, the combination of two parts hinged together, a clip for locking said members in clamping position upon a pipe, gripping blocks one pivotally mounted in each of said members for engaging the pipe and holding it against rotation, and resilient means mounted at both sides of each of said gripping blocks against which said blocks rest when the pipe is held against turning through the medium of the elevator.
9. In an elevator, the combination of two parts hinged together, a clip for locking said members in clamping position upon a pipe, gripping blocks one pivotally mounted in each of said members for engaging the pipe and holding it against rotation, blocks of rubber mounted in suitable sockets in said members at both sides of each of said gripping blocks, and set-screws one for each of said blocks of rubber adapted to adjust the block of rubber toward the gripping block.
10. In an elevator, the combination of two members hinged together, a clip for locking said members in clamping position upon a pipe, and gripping blocks one pivotally mounted in each of said members for engaging the pipe and holding it against rotation, each of said blocks being of a longer radius about its pivot point at its edges than at its central point whereby as said blocks are turned on their pivots they are tightened upon the pipe.

MATTHEW T. CHAPMAN.
